UNITED STATES PATENT OFFICE.

PERCY H. THOMAS, OF MONTCLAIR, NEW JERSEY, ASSIGNOR TO COOPER HEWITT ELECTRIC COMPANY, OF NEW YORK, N. Y., A CORPORATION OF NEW YORK.

AUTOMATIC REGULATING DEVICE.

No. 877,258.

Specification of Letters Patent.

Patented Jan. 21, 1908.

Original application filed February 17, 1903, Serial No. 143,760. Divided and this application filed June 16, 1905. Serial No. 265,501.

To all whom it may concern:

Be it known that I, PERCY H. THOMAS, a citizen of the United States, and resident of Montclair, county of Essex, State of New Jersey, have invented certain new and useful Improvements in Automatic Regulating Devices, of which the following is a specification.

In another application filed by me on the 10 7th day of February, 1903, and bearing the Serial Number 142,255 I have shown and described a system of electrical distribution in which means are provided for delivering to a work or consumption circuit, the proper 15 amount of electrical energy for satisfying the momentary needs of the service, such means depending on selecting and utilizing portions of successive cycles which shall be adapted to deliver the desired energy.

20 The system referred to is adapted to be controlled through the action of current rectifiers which permit the flow of current in one direction and oppose a practically prohibitive resistance to the flow of current 25 in the opposite direction, coupled with devices in the supply circuit for so accelerating the energy derived from the source as to predetermine the time when energy shall begin to traverse the rectifiers.

30 It should be understood that the apparatus described as a rectifier is characterized by a reluctance to starting which appears particularly at one of the electrodes. When current is applied to the apparatus, an electric strain is produced at the said electrode and by increasing this strain to the breaking point, the apparatus may be started into operation, after which it will continue to operate until the zero point of the wave is 35 reached. The moment of starting an apparatus of this character can be predetermined by selecting the time when the critical breaking down strain is applied to the apparatus. The time being selected so as to 40 coincide with a certain portion of a cycle, The energy made use of in the receiving or consumption circuit may be of any desired amount within the capacity of the supply circuit. Should it be desired to deliver to 45 the receiving circuit, for example, a current of low voltage, the starting can be so timed as to utilize the latter part of a cycle or a succession of cycles, where the voltage is low, while by a proper adjustment of the controlling devices, the part of the cycle which is

utilized may be shifted so as to apply to the receiving circuit the maximum voltage, if desired, or any intermediate voltage.

In the system described and shown in the application referred to, the regulation of the energy delivered to the receiving circuit is voluntarily controlled according to the known needs of such circuit. By the present invention provision is made for automatically supplying to the receiving circuit 65 an amount of energy corresponding to the load on such circuit, thereby tending to create conditions in the consumption circuit adapted to the existing needs thereof. The means by which such automatic regulation 70 is accomplished are illustrated in the accompanying drawings, in which

Figures 1 and 2 are diagrams of systems adapted to accomplish the results named; and Fig. 3 is a diagram of a direct current 75 system together with certain details of apparatus which may be made use of in connection with such system.

In Fig. 1, main conductors 1 and 2 are shown, the same being assumed to be connected with a source of alternating current. Leading from these mains are wires 3 and 4 which are suitably connected with receiving circuit wires 5 and 6. The receiving circuit may contain translating devices, 7 and 8, 85 of any suitable character. Between the wires 3 and 4 I may interpose the primary, 9, of a transformer, and also a suitable inductance 10.

The primary 9 may be provided with 90 means of well-known character, varying the applied voltage, as illustrated by the leads, 11, 11, and the movable switch arm 12. The latter is connected with a longitudinally movable arm, 13, pivoted to a bell-crank lever, 14, as shown. The bell-crank lever is pivoted at 15, and a counterweight, 16, is provided for drawing the left hand end of the lever downward when the opposite end is relieved, as will be presently explained. 100 The said opposite end is connected by a link, 17, with the core, 18, of a shunt coil, 19, the said core being also wound with a series coil 20. It will be observed that the resistance represented at 11 is connected in shunt relation with the primary 9 so that when more resistance is introduced into the shunt circuit as by the movement of the bell crank lever to the left, the voltage applied to the primary 9 will be greater, while the voltage 110

applied to the said primary will be decreased by the cutting out of resistance through the movement of the said bell crank lever to the right.

5 Between the conductors 4 and 6, I insert a gas or vapor electric apparatus, 23, consisting of a suitable container inclosing a conducting gas or vapor and provided with electrodes 24 and 25.

10 As has already been explained, an electrode reluctance is set up whenever current is applied in a given direction to an apparatus of this sort, and current will not pass through the apparatus until this reluctance 15 has been broken down. In the present instance, this reluctance appears alternately at the two electrodes, and is alternately broken down by means hereinafter to be described. This breaking down takes place through the 20 action of auxiliary electrical energy added to the electric strain which is produced at each electrode when current is applied to the terminals or electrodes of the apparatus.

Not only do the means about to be described provide for the alternate breaking down of the electrode reluctance, but they 25 also bring it about that the time at which the critical or breaking down strain shall be applied to each electrode may be predetermined. This being the case, only such portions of each cycle as follow the starting point of the cycle will be applied to the consumption circuit and only until the zero point of the wave is reached.

30 It will be observed that each electrode is surrounded by a starting band, one of which is indicated at 26, and the other at 27. It will also be seen that each of the starting bands is connected by a conductor, 28, with 35 the circuit on the opposite side of the apparatus. It has been found that the presence of such starting bands facilitates the starting of apparatus of the character described, and a convenient mode of applying the critical strain to the apparatus is by 40 making the application through the said starting bands. This is done in the present instance, by means of two secondaries, 21 and 22, for the transformer primary 9, one of 45 said secondaries being included between the conductor 3 (or 4) and the starting band 27, and the other being included between the conductor 3 (or 4) and the starting band 26.

50 The average energy delivered to the receiving circuit depends upon the portions of the cycles of the supply actually utilized. This portion may be determined by the relative point in the cycle at which energy is first allowed to traverse the device 23. On 55 account of the nature of this device current flow is initiated at the instant the strain introduced by starting bands 26 and 27, exceeds the critical amount. This time may be varied either by increasing the natural maximum voltage of the secondary windings

60 21 and 22 so that the critical strain is reached at an earlier point of every cycle or by the variation of the phase of the electro-motive-force of 21 and 22 so that any given point of either cycle is reached earlier or later relative to the supply cycle for the receiving circuit. These results may be produced by the arrangement of circuits shown in Fig. 1. The function of the inductance 10 is to control the phase and quantity of current supplied to the divided circuit consisting of the primary 9 and the shunting resistance 11. By varying the value of the resistance 11, different portions of the total current passing the coil 10 are caused to pass through the 65 primary 9 and to give the variation of phase and magnitude of the current actually traversing 9.

70 By the proper adjustment of the circuit of the said primary through the movable arm 13 and the movable contact 12, the degree of acceleration or retardation of the secondary electro-motive-forces may be controlled so as to predetermine the times when the critical strains are applied to the respective 75 starting bands. If the proper adjustment is made, the starting of the device 23 in alternatively opposite directions, and consequently the delivery of current to the receiving circuit may be made at selected 80 points in the cycles, whereby the average amount of energy delivered to the receiving circuit can be regulated. The system shown is intended to make such regulation dependent upon the demands of the receiving circuit, this being accomplished through the 85 medium of the differentially wound shunt and series coils 19 and 20, and the parts associated therewith. For example, should the voltage in the receiving circuit decrease, 90 the core 18 within these coils will be lifted through the action of the counterweight 16 and, through the illustrated system of levers, the contact 12 will be moved towards the left, thereby shunting a smaller portion 95 of the current around the primary 9. On the other hand, should the voltage increase in the receiving circuit, the described action 100 will be reversed.

105 The exact method of operation of the device of this figure will be understood from the following: Assuming that a satisfactory condition of operation has been reached and beginning with the commencement of some cycle there will be applied from wires 3 and 4 across the work circuit and the device 23 gradually an electric pressure which will in general be insufficient to overcome the negative electrode reluctance thereof so that no current passes therethrough in the initial 110 stages, but with the increasing strain this condition is more nearly reached as the alternation proceeds. At the same time current is passing through the coil 10 and the transformer primary 9 due to the voltage upon the 115 120 125 130

wires 3 and 4 which in turn causes a strain to be applied to the starting bands 26 and 27 from the transformer secondaries 21 and 22. When now this strain becomes sufficient, for example, when one-third of the alternation has passed, the negative electrode reluctance of whichever of the two electrodes 24 and 25 is negative will be overcome and current will flow from the wires 3 and 4, the wires 5 and 6 to the work circuit. This current flow will continue in virtue of the characteristics of the negative electrode until the current drops nearly or quite to zero when the negative electrode reluctance of the negative electrode will reestablish itself. As now voltage rises in the next alternation in the opposite direction, the same series of phenomena will follow, the current however flowing in the opposite direction. The first third of the alternation will, as before, be a time of no current flow, while the remaining two-thirds, or thereabout, will be a time of supply of energy. Each alternation will then be a repetition of one of the two just described and energy will be impressed steadily upon the work circuit from the mains in a definite quantity.

Supposing now that more energy is required in the supply circuit, as by dropping of the potential between the wires 5 and 6 which will result from a change in the demands, for example, of the motor 8. The coil 19 being excited by this potential will be reduced in its attraction on the core 18 which will allow the counter weight 16 to pull the contact 12 to the left, increasing the effective proportion of the resistance 11. This will increase the voltage upon the transformer primary 9 and at the same time advance the phase of the electromotive force therein, as will be seen from the following conditions: The coil 10 has a tendency to determine the phase of the current passing therethrough in view of its power to absorb voltage. Whatever current passes through the coil 10 divides between the primary 9 and the resistance 11. The two portions will be out of phase since the path 11 is non-inductive, while the path 9 is inductive, the latter lagging behind the former. An increase of the resistance 11 now forces a larger proportion of the total current passing through 10 through the transformer primary 9, thus increasing its magnetizing power and advancing its phase since the component received from 11 is leading with reference to the previous current in 9. As a net result, the critical voltage which is sufficient to overcome the negative electrode reluctance of 24 or 25, whichever happens to be the negative electrode, will occur at an earlier part of the alternation, perhaps one-fifth from the beginning, so that current will flow to the work circuit during approximately five-sixths of the alternation instead of two-thirds, which

will tend to maintain the proper magnitude of voltage between the wires 5 and 6.

The relation of the currents in the parts 10, 9 and 11 can be more clearly followed by means of the diagram shown in Fig. 4. In this figure OY represents the reference line and OA a line revolving in the direction shown by the arrow whose projection upon OY may represent the current in the coil 10. The position in which the line OA is shown in the figure is chosen by accident. This current divides between 9 and 11. Since 9 is inductive and 11 is ohmic the current in the latter will be 90 degrees ahead of the current in the former. If we choose such an adjustment of the resistance 11 that the currents in 9 and 11 are numerically substantially equal they may be represented respectively by OB and OC. OB thus represents the magnetizing current in the current 9. If now the resistance 11 be greatly increased to reduce the current therein to a small value as OE the current in 9 will be OD. From this it is evident that by the increase in resistance of 11 the current in 9 has been advanced from OB to OD and at the same time increased in numerical value.

Similarly, the coil 20 may act to maintain the proper flow of current in the work circuit, or other regulating relations may be obtained.

It should be noted that, except where special effects are desired, the coil 20 will be so designed as not to have sufficient power to neutralize the degree of pull of coil 19 on decreased voltage due to increased lead current; otherwise, the object of the device might be defeated; and in general it is necessary to so proportion the parts that the desired result which may vary through a very wide range of conditions will be secured as may be readily done by any one skilled in the art.

In cases where it is not desired to have the motion of the core 18 correspond exactly to the action of the coil 19 the coil 20 connected in series with the receiving circuit may be added to accelerate or diminish the action of the shunt coil 19.

Any suitable means or method whereby the effects accomplished through the mechanical means herein described may be used in place of such mechanical means, if desired.

In Fig. 2, 29 represents an alternating current generator, and 30 an exciter therefor. The mains 1 and 2 are here connected with the conductors 5 and 6, through a gas or vapor electric apparatus 31 which serves the purposes of a rectifier, permitting the passage of current in the direction indicated by the arrow, and preventing the discharge of current in the opposite direction under ordinary conditions. The starting band 32 is connected to the conductor 2, and the primary 9 is here placed in series with a resistance, 33,

both the primary and the resistance being joined between the mains 1 and 2. The secondary, 34, is here provided with variable connections, the movable contact, 35, for 5 accomplishing this being here connected with a link, 36, connected to a lever, 37, pivoted at 38. The opposite end of this lever is connected by a link, 39, with the core, 40, of a coil, 41, connected as a shunt 10 coil between the conductors 1 and 2. Translating devices are shown at 42, 43, between the receiving mains 5 and 6. At 101 I show a vapor converter the function of which is to supply the exciter 30 with currents of one 15 direction only. It accomplishes this purpose in view with negative electrode reluctance at one of the electrodes which permits the flow of current in one direction and suppresses it in another. The starting band 100 20 serves as a means for breaking down the reluctance of the negative electrode to allow the passage of current in the proper direction. The starting band 100 is connected through the pivot 38 and the link 36 with the 25 sliding contact 35. In the system illustrated in this diagram one half of the impulses from the generator pass into the receiving circuit, the other impulses being suppressed. It is, of course, understood that the energy taken 30 through the converter 101 may be taken from the generator during those impulses which are wrongly directed for use in the devices 42 and 43 as is so shown in Fig. 2, though by oppositely directing the converter 35 101 the impulses through the exciter 30 may be taken at the same time as impulses through the converter 31.

The proper operation of the apparatus will be clear from the following: When voltage in 40 the proper direction is impressed by the generator 29 upon the mains 1 and 2, current will flow through the converter 31 in view of the strain introduced upon the negative electrode thereof by the connection of the starting band 32 to the wire 2 and will pass to the wires 5 and 6 and through the various devices connected thereto. When the impulse of the generator 29 is in the opposite direction, no current can pass the converter 31 45 since no means are provided for breaking down the negative electrode reluctance of the negative electrode under these conditions. The excitation of the generator 29 is secured through the unidirectional impulses 50 passed from the mains 1 and 2 through the converter 101 to the exciter 30 here shown as a field coil. These impulses can pass through the converter 101 in one direction in virtue of the impression of a critical strain on 55 the starting band 100 from the secondary 34 of the transformer primary 9 which is connected through the controlling resistance 33 across the mains 1 and 2. Automatic control of the energy supplied to the mains 5 and 60 60 from the generator 29 is secured by gov-

erning the strength of the excitation in 30 by the shunt coil 41 and coöperating plunger 40. When a definite condition of transmission of energy exists, a certain magnetizing current passes through the resistance 33 to 70 the primary 9 and there excites the secondary 34 which impresses a critical strain upon the starting band 100 of the converter 101 at the desired instant to allow a sufficient quantity of unidirectional current to flow to produce the proper generator voltage. Should a higher voltage be required as, for example, by the dropping of the potential between 5 and 6, the coil 41 will decrease the pull inserted upon the core 40, allowing the counterweight to drop the lever 36 and the movable contact 35 which will include a larger portion of the secondary 34 in the circuit to the starting band 100 and the resulting higher voltage will cause the critical strain 80 upon the starting band 100 to accrue at an earlier time, thus increasing the amount of exciting energy and raising the generator voltage. Similarly with the reverse operation.

At 101 I show a vapor converter, the function of which is to supply the exciter 30 with currents of one direction only. It accomplishes this purpose in view of the negative electrode reluctance at one of the electrodes which permits current flow in one 95 direction and suppresses it in the other.

In Fig. 3, I have illustrated the application of my invention to a direct current supply circuit, the mains of which are shown at 44 and 45. The receiving circuit has the 100 main conductors, 46 and 47. The translating devices are shown at 48 and 49.

For convenience of illustration, I here show a rectifier, 50, which under normal conditions permits a continuous flow of current in the direction of the arrow. If, however, a device such as a condenser, 51, is momentarily introduced into the circuit, the energy withdrawn during such period from the mains is sufficient to reduce the energy in 105 said mains below the point where it will be transmitted through the device 50. Consequently, the circuit will be momentarily opened and can only be started again by the creation within the device of a critical or 110 breaking down strain. The impulse tending to create this strain may be applied as before to the starting band 52 of the device 50, the said band being connected through the secondary, 53, of a transformer to the opposite main 45. The primary, 54, of the said transformer is connected by one terminal to the main 44, and by the other to a brush, 55, which coöperates with an insulating disk, 56, carrying a conducting piece, 57, on its periphery. A second brush, 58, also coöperating with said disk and conducting piece and having a certain amount of lead with respect to the brush 55, is joined by a wire, 59, with the main 45. The said disk 56 is mounted upon 115 120 125 130

a shaft, 60, so as to be capable of partial rotation thereon, and through a hub, 61, attached to the disk it has a clutch connection with the hub, 85, of a similar disk, 62, the latter hub 5 being adapted to engage with the hub 61 by means of angularly placed teeth 63, as shown. The disk 62 carries a conducting piece, 64, adapted to coöperate with brushes, 65 and 66, the latter of which is connected by a wire, 67, with the main conductor 44, and the former of which is connected by a wire, 68, with one side of the condenser 51, the opposite side of which is joined to the conductor 45.

The disk 52 is feathered to the shaft 60 and rotates therewith, while the disk 56 is also adapted to rotate with the shaft but only by reason of the engagement of the teeth 63, 63 on the respective hubs. The shaft 60 is rotated by means of a motor, 69. During its rotation, the shaft carries with it the disks 56 and 62, and at intervals brings the conducting plates 57 and 64 into contact with the respective pairs of brushes connected on the one hand to the wire 45 and the primary 54, and 20 on the other to the wire 44 and the condenser 51. Accordingly, once in each rotation of the shaft, the circuit of the condenser 51 is closed, thereby momentarily interrupting the flow of current through the device 50, and 25 the circuit of the primary 54 is also closed, the respective closures of the circuit being so timed that the condenser circuit shall be completed just in advance of the closure of the circuit of the primary 54. The closure of 30 the former circuit acts to withdraw the energy from the rectifier 50 to practically open the circuit at that point, while the closure of the circuit through the primary acts to charge the secondary to impress upon the 35 starting band 52 a critical strain which starts the current once more through the rectifier.

It is evident that the disks 56 and 62 may have their angular relations varied by moving one disk towards the other and thereby 40 causing the disk 56 to be rotated somewhat upon the shaft 60. The relative time at which the circuit of the primary 54 shall be completed after the completion of the condenser circuit is, therefore, variable as indicated. This variation can be accomplished through the action of a shunt circuit, 45 70 and 71, including a coil, 72, such shunt circuit being connected on opposite sides of a resistance, 73, in the main conductor 47. When the current delivered to the receiving 50 circuit becomes excessive by reason of a change of load in such circuit or from any other cause, the solenoid coil 72 will become charged beyond the normal and will tend to 55 draw down its core, 74, and to shift the system of levers represented by the link, 75, the angular lever, 76, and the levers, 77, 78, 79 and 80, connected therewith. The drawing in of the core 74, manifestly acts upon 60 the disk 56 so as to cause it to be moved to-

wards the disk 62, thus increasing the lead of the brushes 55 and 58, as compared with the brushes 65 and 66. On the other hand, should the solenoid 72, become less strongly charged by reason of a lowering of the voltage in the work circuit, an opposite action 70 would take place by reason of the releasing of the system of levers more and more into the power of a weight, 82, acting in opposition to the downward pull of the solenoid 72. 75

In another application filed February 17, 1903, Serial Number 143,760, of which this application is a division, claims are made upon certain methods of operation disclosed herein.

In still another application, filed June 14, 1907, Serial Number 378,896, constituting a division hereof, claims are made upon certain specific disclosures made herein.

I claim as my invention:—

1. In a system of electrical distribution in which a receiving circuit is fed from an alternating supply the combination of a vapor electric device requiring a reinforced potential to start the current flow, means for applying such reinforced potential to said device, with means for varying the time of application of said reinforced potential, together with means responsive to the delivered energy for controlling said varying means.

2. In a system of electrical distribution in which a receiving circuit is fed from an alternating supply the combination of a vapor electric device requiring a reinforced potential, and a starting band for applying said reinforced potential to said device, with means for varying the time of application of said reinforced potential, together with means responsive to the delivered energy for controlling said varying means.

3. In a system of electrical distribution in which a receiving circuit is fed from an intermittent supply the combination of a gas or vapor electric device requiring the application of starting means after any cessation of current and suitable starting means therefore, with means for varying the time of application of said starting means, together with means responsive to the delivered energy for controlling said varying means.

4. In a system of electrical distribution in which a receiving circuit is fed from an alternating current supply the combination of a vapor electric device requiring a reinforced potential to start current flow and means for applying such reinforced potential to said device, with means for advancing and retarding the application of said reinforced potential, together with means for controlling the last named means in response to appropriate change in the circuit requirements.

5. In a system of electrical distribution in which a receiving circuit is fed from an al-

80

ternating current supply, the combination of a vapor electric device requiring a reinforced potential to start current flow and means for applying such reinforced potential to said device, with means for advancing and retarding the application of said reinforced potential, together with means for controlling the last named means in response to appropriate change in the circuit requirements, said means including at least one electro-magnet.

6. In a system of electrical distribution in which a receiving circuit is fed from an alternating current supply, the combination of a vapor electric device requiring a reinforced potential to start current flow, and means for applying such reinforced potential to said devices, with means for advancing and retarding the application of reinforced potential, together with means for controlling the last named means in response to appropriate change in the circuit requirements, said means including two coöperating magnet coils responsive to different characteristics 25 of the circuits.

7. In a system of electrical distribution from an alternating supply the combination of a vapor electric device requiring a starting means after any cessation of current and suitable starting means therefor, with means for operating said starting means during impulses of the supply when each are directed in a predetermined direction.

8. In a system of electrical distribution in which energy is delivered to the work circuit from a supply circuit through a vapor electric device the combination of means for interrupting current between the work circuit and the supply and means for applying a critical re-inforced potential for reestablishing said current flow, with means independent of the work circuit and supply circuit for varying and controlling the time of application of the critical reinforced potential.

9. In a system of electrical distribution in which energy is delivered to the work circuit from a supply circuit through a vapor electric device the combination of means for interrupting current between the work circuit and the supply and means for applying a critical reinforced potential for reestablishing said current flow, with means independent of the work circuit and supply circuit for varying and controlling the time of application of the critical reinforced potential, the last named means being automatically responsive to the circuit conditions.

10. In a system of electrical distribution wherein a supply circuit carrying an alternating current is connected with a receiving circuit subject to variations of load, and wherein current rectifiers characterized by a reluctance to starting are interposed in the

system at a suitable point or points, means for adapting the supply to the needs of the receiving system, such means consisting of a transformer, and devices acted upon by variations of load in the receiving circuit for accelerating or retarding the secondary electro-motive-force of the transformer.

11. In a system of electrical distribution wherein a supply circuit carrying an alternating current is connected with a receiving circuit subject to variations of load, and wherein current rectifiers characterized by a reluctance to starting are interposed in the system at a suitable point or points, means for adapting the supply to the needs of the receiving system, such means consisting of a transformer, a variable element acting on said transformer, an electro-magnetic device controlling the said variable element and determining the time or times at which the secondary electro-motive-force of the said transformer shall be applied to the current rectifier or rectifiers.

12. In a system of electrical distribution wherein a supply circuit carrying an alternating current is connected with a receiving circuit subject to variations of load, and wherein current rectifiers characterized by a reluctance to starting are interposed in the system at a suitable point or points, means for adapting the supply to the needs of the receiving system, such means consisting of a transformer, and devices for adjusting the secondary electro-motive-force thereof, a lever adapted to cause such adjustment by its varying positions, and one or more coils adapted to alter the position of the said lever in response to variations of load in the receiving circuit.

13. In a system of electrical distribution wherein a supply circuit carrying an alternating current is connected with a receiving circuit subject to variations of load, and wherein current rectifiers characterized by a reluctance to starting are interposed in the system at a suitable point or points, means for adapting the supply to the needs of the receiving system, such means consisting of a transformer, and devices for adjusting the secondary electro-motive-force thereof, a lever adapted to cause such adjustment by its varying positions, and a series coil and a shunt coil connected with the receiving circuit, the said coils acting differentially upon the said arm in response to variations of load in the receiving circuit.

14. In a system of electrical distribution in which a receiving circuit is fed from an alternating current supply the combination of a vapor electric device requiring a reinforced potential to start current flow, and means of applying such reinforced potential to said device with means for varying the time of application of said reinforced potential, together with means responsive to the

delivered energy for controlling said varying means, said means for varying the application of the reinforced electro-motive force including means for changing the relative 5 phase of an exciting transformer.

15. In a system of electrical distribution in which a receiving circuit is fed from an alternating current supply the combination of a vapor electric device requiring a reinforced potential to start current flow, and means for applying such reinforced potential to said device, with means for varying the time of application of said reinforced potential, together with means responsive to 10 15 the delivered energy for controlling said varying means, said last named means including a coil in shunt upon the receiving circuit.

16. In a system of electrical distribution in which a work circuit is supplied from an alternating current generator, means for controlling the time of application of supply to work circuit in each alternation, said means being variable, together with means for controlling said variable means to deliver a suitable portion of the supply cycles 20 25 to the work circuit.

Signed at New York, in the county of New York, and State of New York, this 14th day of June A. D. 1905.
